[57] CLAIM

The ornamental design for the infuser base, as shown and described.

DESCRIPTION

FIG. 1 is a perspective view of the infuser base showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a pre-rolled state of the infuser base with the base portion removed for ease of illustration; and,

FIG. 9 is a left side elevational view of the infuser base. The broken line showing of an infuser is for illustrative purposes only and forms no part of the claimed design.
